Attorney

UNITED STATES PATENT OFFICE.

PRESLEY G. BAILY, OF EAGLE ROCK CITY, CALIFORNIA.

LID-REMOVING DEVICE.

Application filed January 10, 1924. Serial No. 635,420.

To all whom it may concern:

Be it known that I, PRESLEY G. BAILY, citizen of the United States, residing at Eagle Rock City, in the county of Los Angeles and State of California, have invented certain new and useful Improvements in Lid-Removing Devices, of which the following is a specification.

This invention relates to certain new and useful improvements in lid removing devices, and has particular reference to an improved means for facilitating removal of jar or can covers or lids of the slip on type.

An object of the invention is to provide a device of the above kind which is simple and durable in construction, as well as efficient in operation.

Another object of the invention is to provide a lid removing device of the above kind which may be readily and easily placed into practical use, and which may be manufactured and marketed at a low cost.

Still another object of the invention is to provide a lid removing device, which may be readily adjusted for use in connection with receptacles of different sizes.

With the above general objects in view and others that will become apparent as the nature of the invention is better understood, the same consists in the novel form, combination, and arrangement of parts hereinafter more fully described, shown in the accompanying drawing and claimed.

In the drawing, wherein like reference characters designate corresponding parts throughout the several views:

Figure 1 is a side elevational view of a lid removing device constructed in accordance with the present invention with the handle portion of the lever partly broken away.

Figure 2 is substantially a top plan view of the device shown in Figure 1 with parts broken away.

Figure 3 is an enlarged perspective view of the lid engaging pawl, and

Figure 4 is an enlarged fragmentary perspective view showing the inner end of the lever.

Referring more in detail to the drawing, the present invention comprises an arcuate body 5, the ends of which are bifurcated to provide superposed leg members 6, between each end of which is disposed the eyed end of a band section 7, a pin 8 being passed through each pair of legs and the adjacent

eye of the adjacent band section 7 to pivotally connect the band sections to the body 5. The band sections 7 have a considerable portion of their opposite end portions slidably overlapped so that the sides of the band may be conveniently enlarged or made smaller to fit the particular jar or can whose cover is to be removed. A U-shaped member 9 forming part of a clamp is engaged over a band section at a point substantially diametrically opposite to the body 5 and pivoted between the legs of this clamp member 9 is a cam cylinder 10 having a handle 11 projecting outwardly therefrom. By rotating the cam cylinder 10, the band sections may be forced into tight engagement with each other and with the intermediate portion of the clamp member 9 so as to retain the band in any desired adjusted size. However, it is to be understood that while this particular clamping means is deemed preferable, any equivalent clamping means may be substituted in lieu thereof if desired.

The intermediate portion of the body 5 is provided with a pair of spaced outwardly projecting arms 12 between which is disposed the inner end portion of a lever 13 and to which said lever is pivoted as at 14 between its ends. The lever 13 carries a suitable handle 15 for facilitating rocking of the same, and the inner end of the lever is bifurcated to provide a pair of legs 16 between which is pivoted the lower end of an angular pawl 17. The lower end of the pawl 17 is reduced at opposite sides to provide a pair of shoulders as at 18 for cooperating with the upper edges of the legs 16 of the lever 13 for limiting swinging movement of said pawl. The angular form of the pawl 17 provides an upper inwardly extending arm 19 for the latter that is bevelled at its free end as at 20 so that the same may be readily and effectively engaged beneath the edge of the receptacle cap or lid when the band composed of the sections 7 are clamped to the body of the receptacle.

In order to prevent the band from slipping downwardly on the body of the receptacle, a hooked member or plate 21 is secured or otherwise rigidly provided on the clamp member 9 so as to project inwardly as shown clearly in Figures 1 and 2.

In operation, the clamp cam cylinder 10 is turned by manipulation of the handle 11

so as to be released from the band sections 7 whereby the band formed by the latter may be enlarged sufficiently to enable the same to be readily slipped over the body of the receptacle. The lever 13 is swung to the position shown in Figure 1 so that the pawl 17 will be lowered in proper position to engage its bevelled end 20 beneath the edge of the receptacle lid or cover. When properly positioned to so engage the pawl 17 with the lid, the bands 17 are pressed together to fit tightly around the receptacle body, and then the handle 11 is manipulated to rotate the cam cylinder 10 to cause binding of the band sections and thereby lock the band tightly on the jar. The handle 15 is then forced downwardly so as to cause the pawl 17 to move upwardly, and due to the end 20 thereof engaging under the lower edge of the lid, the latter will be effectively pried off of the top of the receptacle body.

From the foregoing description, it is believed that the construction and operation, as well as the advantages of the present invention will be readily understood and appreciated by those skilled in the art.

What I claim as new is:

1. In a lid removing device of the character described, a body, an adjustable band carried by the body for securing the latter upon a receptacle, a lever pivotally mounted upon said body and having a pawl pivoted to the inner end thereof, said pawl having an inwardly projected end portion adapted to engage under the lower edge of the lid to be removed whereby said lid will be forced upwardly from the receptacle body when the lever is swung, said adjustable band comprising band sections having slidably overlapping end portions whereby the diameter of the band may be varied, and clamping means for retaining the overlapping ends of the band sections against sliding movement relative to each other whereby the band may be retained in any desired adjusted size.

2. In a lid removing device of the character described, a body, an adjustable band carried by the body for securing the latter upon a receptacle, a lever pivotally mounted upon said body and having a pawl pivoted to the inner end thereof, said pawl having an inwardly projected end portion adapted to engage under the lower edge of the lid to be removed whereby said lid will be forced upwardly from the receptacle body when the lever is swung, said adjustable band comprising band sections having slidably overlapping end portions whereby the diameter of the band may be varied, and clamping means for retaining the overlapping ends of the band sections against sliding movement relative to each other whereby the band may be retained in any desired adjusted size, and an inwardly projecting hook member carried by the clamp for engagement with the jaw to prevent slipping of the device downwardly onto the receptacle body.

3. In a lid removing device of the character described, an arcuate body provided with bifurcated ends forming pairs of upper and lower legs, band sections having ends provided with eyes disposed between said legs, pins extending through the legs and the eyes of the band sections for attaching the latter to the body, the opposite ends of said band sections being slidably overlapped and equipped with means for retaining the same against relative sliding movement, outwardly projecting legs provided upon the intermediate portion of the body, a lever pivoted between its ends and disposed between the last named legs for vertical rocking movement, and an angular pawl pivoted to the inner end of the lever and having an inwardly projecting free end portion adapted for positioning under the lower edge of the lid to be removed.

In testimony whereof I affix my signature.

PRESLEY G. BAILY.
